(57) **CLAIM**

We claim the ornamental design for guitar strap packaging, as shown and described.

DESCRIPTION

FIG. 1 is a perspective view showing our new design;
FIG. 2 is a front view thereof;
FIG. 3 is a top view thereof;
FIG. 4 is a bottom view thereof;
FIG. 5 is a left side view thereof;
FIG. 6 is a right side view thereof; and,
FIG. 7 is left side view thereof, shown in its environmental use. The broken lines are for illustrative purpose only and form no part of the claimed design.
